(57) **CLAIM**

The ornamental design for a shoe, as shown and described.

DESCRIPTION

FIG. 1 is a bottom rear perspective view of a shoe showing my new design;

FIG. 2 is a bottom view thereof;

FIG. 3 is a bottom front perspective view thereof; and,
FIG. 4 is an alternate bottom front perspective view thereof.
The unshaded broken line region within the shaded area forms no part of the claimed design. The broken lines depicting the remainder of the shoe form no part of the claimed design.**1 Claim, 4 Drawing Sheets**| (56)	References Cited	2014/0259747 A1*	9/2014	Baudouin	A43B 13/141
